POWER UNIT FOR A BLENDER OR THE LIKE

Alfred W. Madl, Glendale, Wis., assignor to Sunbeam Corporation, Chicago, Ill., a corporation of Illinois

Filed June 3, 1969, Ser. No. 17,495

Term of patent 14 years

Int. Cl. D7—05

U.S. Cl. D89—1

Fig. 1.

11

Fig. 2.

Fig. 3.

Fig. 4.

Fig. 5.

FIG. 1 is a perspective view of a power unit for a blender or the like embodying my new design;

FIG. 2 is a top plan view thereof;

FIG. 3 is a top plan view thereof;

FIG. 4 is a front elevational view thereof; and

FIG. 5 is a rear elevational view thereof.

I claim:

The ornamental design for a power unit for a blender or the like, as shown.
